CLAIM

The ornamental design for a capsule endoscope starter, as shown and described.

DESCRIPTION

An article to which my new design is applied is a starter of a medical swallowable endoscope (the so-called capsule endoscope) used in a wireless in vivo information acquiring system for collecting in vivo information. The starter includes a permanent magnet. The capsule endoscope, when loaded into the starter, is applied with magnet force, thereby starting.

FIG. 1 is a front view of a capsule endoscope starter showing my new design;

FIG. 2 is a rear view thereof;

FIG. 3 is a plan view thereof;

FIG. 4 is a left side view thereof; and,

FIG. 5 is a cross sectional view taken along line A—A of FIG. 1.
